(No Model.)

J. H. DALE.
TENSION DEVICE FOR CABLE RAILWAYS.

No. 364,489.

Patented June 7, 1887.

UNITED STATES PATENT OFFICE.

JOHN H. DALE, OF PHILADELPHIA, PENNSYLVANIA, ASSIGNOR OF ONE-HALF TO EDWARD D. DOUGHERTY, OF SAME PLACE.

TENSION DEVICE FOR CABLE RAILWAYS.

SPECIFICATION forming part of Letters Patent No. 364,489, dated June 7, 1887.

Application filed December 9, 1886. Serial No. 221,107. (No model.)

To all whom it may concern:

Be it known that I, JOHN H. DALE, of Philadelphia, in the county of Philadelphia and State of Pennsylvania, have invented certain new and useful Improvements in Tension Devices for Cable Railways; and I do hereby declare the following to be a full, clear, and exact description of the invention, such as will enable others skilled in the art to which it applies to make and use the same.

My invention relates to tension devices for cable railways.

The object of my present invention is to provide a compact mechanism whereby the tension of a traction-cable may be regulated and the slack or looseness of the cable occasioned by stretching or other causes may be taken up automatically after a proper adjustment of working parts of the device in relation to the cable is made.

A further object is to provide a tension-regulating device that is simple in construction, reliable in action, and will be accurately adjustable to suit the varying strain on the running cable from changing draft resistance.

A further object is to construct a self-adjusting or automatic tension-regulator, that will have few working parts, that are all accessible, and may be manufactured and kept in working condition at a low cost for construction and repairs.

With these ends in view my invention consists in certain features of construction and combinations of parts, that will be hereinafter described, and pointed out in the claims.

In the accompanying drawings, Figure 1 is a side elevation of the tension apparatus. Fig. 2 is a plan view of the device.

Referring to the drawings, A represents two similar vertical standards or frames, made of metal or other proper material. These upright frames are preferably constructed wider at the base A', to give necessary stability and brace them to resist side strains. The side edges, a a, are inclined toward each other, as shown in Fig. 1, and at the top are joined to form half-shells b. A cap, b', is fitted in place upon each standard to form, with the half-shells b, two journal-boxes, whose axial centers are in the same horizontal plane.

Upon the standards A the twin walking-beams B are mounted. These beams B are made preferably of metal, and have trunnions c, formed integral with their sides. These trunnions or side projecting journals are directly opposite each other, and are preferably located at a central point in the length of the beams.

The beams B are webbed in a manner usual to secure necessary strength and reasonable lightness, and are secured together by the transverse bolts e e', and also by the journal-shafts g g', that are inserted in holes made for their reception in the ends of the walking-beams B.

The grooved pulleys C D are rotatively mounted on the transverse shafts g g'. They are preferably made of equal size, and their perforated hubs are made of a proper length each side of the grooved centers of the wheels, so that the grooved faces of these pulleys will be in the same vertical plane.

A proper frame, I, is provided at the rear of the upright frame A A, to support horizontally the sliding carriage h, which latter is provided for the support of the idler-pulley E. A windlass, F, is attached to work on the side of the frame I, and by rope or chain and sheave-blocks G G the pulley E may be made to recede from the frame A A.

At a proper point above the frame I two similar grooved pulleys, I', are shaft-mounted to rotate together. Above the pulleys and to their rear two similar pulleys, J, are rotatively adjusted to any suitable frame or fixed point. The pulleys I' and J are placed in the same vertical plane, respectively, so that the parallel chains or wire ropes H H' will work properly when located in the grooves of these pulleys.

The chains or ropes H H' are secured to the lower shaft, g', that is affixed to the walking-beams B, and extend rearwardly in running contact with the pulleys I' and over the pulleys J, and thence downward to connect to the weight K. This weight K may be a solid block, or may be in the form of a box, with a suitable means of connection to its supporting ropes or chains, the box being of a capacity to hold weight in excess of the maximum de-

mands of the service. Lead or other heavy material may be placed therein in proper amount to attain the desired result.

In operation the endless cable M is wound 5 around the driving-drum L, then adjusted in position on the pulleys C D, and also on the pulley E. The cable is stretched to remove "slack" or looseness by drawing the carriage h, with its mounted pulley E, to the rear by 10 the windlass F and chain blocks G G. The attached chains or wire ropes H H' should be of such relative length that the weight K will be raised free and thus suspended, as shown in Fig. 1, when any increase of draft on the 15 running cable by the attachment of additional cars thereto causes a change in tension of the cable. This change will be properly compensated for by the vibration of the beam and the elevation proportionately of the end g' of the 20 walking-beams B, as it is evident that the upward movement of the pulley C and its supporting-shaft g' will pull the ropes or chains H H' and thus cause an elevation of the weight K. A decrease of draft strain will be compensated for and an equilibrium be maintained 25 by the descent of the weight K.

It is apparent from the foregoing that this compensating device will adjust the tension of the cable automatically to suit variations 30 caused by the "hooking on" or dropping of cars on the line, when a proper adjustment of relative parts has been provided by a graduation of the suspended weight to the maximum strain it is designed to counteract.

35 The several elements embodied in this compensating device are of simple construction and consequent cheap production, and, as ready access is afforded to adjust and lubri-

cate the running bearings, excessive wear of frictional surfaces is avoided, and consequent 40 cost for repairs is reduced to a minimum figure.

Minor changes may be made in the construction of this invention without departure from its spirit. I therefore do not wish to restrict 45 myself to exact forms and arrangement of parts shown; but,

Having fully described my invention, what I claim as new, and desire to secure by Letters Patent, is,

1. In a tension device for endless cables, the combination, with a walking-beam carrying pulleys and an endless cable, of a sliding carriage carrying an idle pulley, a weight, and a flexible device connecting the weight and 55 walking-beam.

2. The combination, with a supported walking-beam having grooved pulleys mounted thereon and an endless cable, of a counteracting weight and a flexible connection between 60 the weight and walking-beam, substantially as set forth.

3. The combination, with an endless cable, of a driving-drum, a supported walking-beam, pulleys on the beam, a sliding carriage carrying a cable-pulley, means for sliding the carriage, two chains or ropes, pulleys to support the chains or ropes, and a variable weight, substantially as set forth.

In testimony whereof I have signed this specification in the presence of two subscribing witnesses.

JOHN H. DALE.
